SOAP HOLDER

Filed May 24, 1928

Inventor:
Howard W. Hindes

By Oren W. Kennedy
Attorney

UNITED STATES PATENT OFFICE

HOWARD W. HINDES, OF WORCESTER, MASSACHUSETTS, ASSIGNOR TO THE WASH-BURN COMPANY, OF WORCESTER, MASSACHUSETTS, A CORPORATION OF MASSACHUSETTS

SOAP HOLDER

Application filed May 24, 1928. Serial No. 280,229.

My invention relates to soap racks, or holders, of a type adapted to be supported between the upright faucets of a wash bowl by means of flexible members forming a part of the holder and which may be readily passed around the faucets so as to support the holder therebetween.

The object of my invention is to provide an improved soap holder of the type designated that may be cheaply and quickly manufactured in large quantities, the flexible supporting members which form part of the holder being so connected to the frame of the holder that they cannot become displaced and will always serve to support the holder firmly between the two faucets. The above and other advantageous features of my invention will hereinafter more fully appear, reference being made to the accompanying drawings in which—

Fig. 1 is a view in front elevation showing my improved soap holder supported between two faucets of a wash basin.

Fig. 2 is a plan view of the holder removed from the faucets.

Fig. 3 is a view in side elevation of the holder with the flexible attaching members removed therefrom.

Fig. 4 is a fragmentary view showing on an enlarged scale the manner of permanently securing the flexible supporting members to the holder.

Like reference characters refer to like parts in the different figures.

As best shown in Figs. 1 and 2, the holder comprises a rectangular frame 1 preferably formed of wire bent to the proper shape with its ends welded at 1a to provide a rigid frame. A series of spaced shallow U-shaped cross members 2, 2 are secured to the long sides of the frame 1 in any suitable manner, as by spot welding the end portions 2a of each cross member to the frame 1. A pair of spaced longitudinal members 3, 3, each also in the form of a shallow U, are secured to both the frame 1 and the cross members 2 as shown preferably by spot welding. With the cross members 2 and the longitudinal members 3 secured to the frame 1 at their ends and to each other, at intermediate points, it

is obvious that the whole assembly provides a very strong and light soap holder which can be produced in large quantities at a low manufacturing cost.

As best shown in Figs. 3 and 4, the end portion 4 of each longitudinal member 3 is bent back on itself beyond the frame 1 and a flexible supporting member 5 is secured at its ends to the spaced end portions 4 projecting from opposite sides of the shorter ends of the frame 1. Each flexible member 5 is preferably in the form of a wire coil with its convolutions 6 normally closely together and with the internal diameter of the coil of such size as to fit over the doubled end portions 4 of the members 3. Each flexible member 5 is secured at its ends to a pair of end portions 4 by contracting the end convolutions 6a on a portion 4a which is of single thickness between the end of the doubled portion 4 and the point of attachment of the member 5 to the frame 1. With each flexible member 5 thus secured to the end portions 4, it is obvious that any force tending to pull the member 5 off of the holder will only result in causing the contracted end convolutions 6a to more closely engage the shoulders 7 at the ends of the doubled portions 4.

When in use my improved holder is adapted to be supported between two spaced faucets of a wash basin as indicated in Fig. 1. Only the shank 8 of each faucet valve is shown, together with the handle 9 by means of which the valve may be turned, and it is obvious that the flexible supporting member 5 at each end of the frame 1 can be stretched enough to slip it over one of the handles 9. The supporting members 5 yield readily when being slipped over a valve handle 9, but when once the holder is in place the supporting members 5 contract and serve to support the holder quite firmly between them as shown in Fig. 1.

From the foregoing, it is apparent that by my invention I have provided an improved soap holder that may be readily applied to the pair of faucets of a wash basin by means of its flexible supporting members. By reason of the fact that the supporting members 5 are anchored to the rigid longitudinal

members 3 of the frame, the members 5 can-
not become displaced and so always serve to
yieldingly support the holder in proper po-
sition between the faucets.

5 I claim,

A holder of the class described comprising
a frame, spaced cross rods secured to oppo-
site sides of said frame, each rod providing
doubled end portions projecting beyond its
10 points of attachment to said frame, and flex-
ible supporting members extending from op-
posite sides of said frame, each supporting
member being in the form of a coiled wire
with its end convolutions surrounding the
15 doubled end portions of a pair of cross rods
and contracted upon the single rod portions
between the doubled portions and the frame,
to hold said supporting member on said dou-
bled end portions.
